UNITED STATES PATENT OFFICE.

GEORGE MARSHALL, OF FREMONT, NEBRASKA.

TRUCK FOR FORMING AND DEPOSITING SHOCKS.

1,073,917.

Specification of Letters Patent. Patented Sept. 23, 1913.

Application filed April 11, 1913. Serial No. 760,383.

To all whom it may concern:

Be it known that I, GEORGE MARSHALL, a citizen of the United States, residing in Fremont, in the county of Dodge and State 5 of Nebraska, have invented certain new and useful Improvements in Trucks for Forming and Depositing Shocks, of which the following is a specification.

The object of my invention is to provide 10 a simple and inexpensive truck equipped with means for expeditiously forming shocks and depositing them in an upright position on the ground as fast as the grain is cut by the binder which precedes it.

15 A further object of my invention is to provide means for bending some of the cap sheaves of the shock to a proper shape for topping or completing the cap for the shock.

In carrying out my invention I provide a 20 truck of suitable construction and to the body of the truck I hinge a platform on which the shocks or bundles of grain are delivered. This platform is provided on opposite sides with uprights or posts to 25 hold the bundles against sidewise movement and at its rear end the platform is provided with perpendicular rods against which the butt ends of the sheaves are placed and which hold the sheaves in place while the 30 shock is being formed and while being dumped. The front end of the platform is provided with hooks which detachably connect with the front of the truck body and it is also provided with laterally projecting 35 handles by means of which it can be swung on its hinge.

In order to bend some of the sheaves for use in forming the cap of the shock, I provide the platform with forwardly projecting 40 rods which coöperate with standards or supports on which sheaves are placed, the arrangement being such that when the platform is dumped or is turned upwardly, sheaves may be placed on said supports and 45 then by turning the platform forwardly the rods before mentioned will engage the sheaves on opposite sides of the supports and bend them to the desired extent.

A number of sheaves are deposited on the 50 platform over a binding rope which is laid on the platform and which is provided at one end with a pulley to facilitate in the binding operation. After a sufficient number of sheaves is thus deposited to form a 55 shock, the rope is tightened and secured and remains on the shock. The front end of

the body of the truck is provided with holders for additional ropes and holders are also provided for holding cords or ropes for securing the cap sheaves.

In the accompanying drawings, Figure 1 shows a side elevation of a shocking truck embodying my improvements with a shock thereon ready to be dumped. Fig. 2 is a similar view showing the position of the 60 platform after it has been turned to deposit the shock on the ground. Fig. 3 is a perspective view on an enlarged scale of part of the mechanism. Figs. 4 and 5 are diagrammatic views illustrating how two 65 sheaves may be supported and bent to give them form for completing the cap. Fig. 6 is a detail view illustrating the devices for bending the sheaves. Figs. 7 to 12 inclusive 70 illustrate how the cap sheaves are applied 75 to the shock. Fig. 7 shows a shock with three cap sheaves thereon looking at the ends of the cap sheaves. Fig. 8 is a similar view looking at the sides of the cap sheaves. Figs. 9 and 10 illustrate how six additional 80 cap sheaves are applied to the three first mentioned. Figs. 11 and 12 illustrate how the bent cap sheaves are applied above the nine sheaves before mentioned and how they 85 are secured in place.

The truck comprises a body A and four wheels B and may be of any suitable construction. It is equipped with a brake C operated by suitable mechanism C' of ordinary construction. The shock platform D is 90 hinged at d to the rear end of the truck body and is normally in the position shown in Fig. 1. At its front end the platform is provided with legs D' which support it and normally hold the platform slightly inclined. 95 These legs D' are each provided with a hook D² engaging an eye d' on the body A. When the hooks are unfastened the weight of the shock turns the platform to the position shown in Fig. 2 and dumps the shock. 100 The uprights or standards G on opposite sides of the platform serve to confine the sheaves while the shock is being formed and the rods R, which are perpendicular to the platform serve to insure an even butt end 105 to the shock and hold it in place while being dumped. An additional number of posts G' may be employed when required and they may be detachably connected to the platform in any suitable manner, as shown their 110 lower ends enter straps g applied to the side edges of the platform. The binding rope H

has one end attached to a pulley-carrying frame. The rope is laid across the frame in rear of the standards G before the sheaves are deposited. After a sufficient number of 5 sheaves have been placed on the platform over the rope, the latter is drawn around the shock, as indicated in Fig. 3, and passed over the pulley h carried by the frame h' and then tightened and secured.

10 K indicates a block provided with grooves k to receive the rope and prevent it from slipping longitudinally on the platform while the shock is being formed. After the shock is bound by the binding rope, the attendants take hold of the handles L and turn the platform on its hinge until it assumes the position shown in Fig. 2, the rods R then assuming a horizontal position when resting on the ground. If the truck now be 15 moved forward, the rods R will slip from under the shock and leave it standing. After this the cap sheaves are applied and this is done in a novel way.

15 On the front part of the body A I erect two standards P which have enlarged upper ends or heads p which are curved to receive the sheaves. These standards and heads co-operate with rods S which extend forwardly from the platform D and beyond and on 20 opposite sides of the standards P. These are for the purpose of bending some of the sheaves to form the top of the cap for the shock. In order to form this cap, after the shock X is bound and delivered, I first place 25 on top of the shock three sheaves V, as shown in Figs. 7 and 8. On top of these I place six sheaves V', as shown in Figs. 9 and 10 and on top of these sheaves V' three bent sheaves V², as shown in Figs. 11 and 12. I 30 then tie the cap to the rope H by cords or ropes H', three cords H' preferably being employed, as indicated in Figs. 11 and 12. This completes the shock with its cap sheaves which I find to be most secure and 35 to well stand the weather. In order to bend the sheaves V² I employ the bending devices P, p and S, before referred to. After the shock has been dumped and when the platform D is in the elevated position shown in 40 Fig. 2, the attendants may place on the heads p of the standards P two sheaves V², as indicated in Fig. 4. It will be observed that two sheaves are operated on at the same time and each sheaf is placed centrally in a head 45 p, then the attendants take hold of the posts G and the handles L and lower the platform. The rods S will engage the sheaves in the manner shown in Fig. 4 and as the platform is further depressed the sheaves 50 will be bent in the manner indicated in Fig. 5. The sheaves will recover or straighten

out to some extent but will still be considerably bent to about the condition shown in Figs. 11 and 12 and in this condition they may be applied on top of the sheaves V' to 55 complete the shock. Preferably I employ two pieces of harness leather S'. These are placed over the sheaves V² when they are on the standards P and before the platform is turned downward. They protect the 60 sheaves and prevent the grain from being threshed out. As soon as the bending operation is completed the harness leather may be removed and the sheaves taken out and placed on the shock.

65 N, N, N indicate racks on which additional binding ropes and ropes for applying the cap sheaves may be stored. The mechanism for forming and depositing the shocks is extremely simple and inexpensive and yet 70 experience has demonstrated that a single shocking truck of this description with two attendants may keep up with a binder of the usual kind and the shocks may be very easily 75 and strongly made.

80 In my application for Patent No. 762,174, filed April 19, 1913 I have shown and claimed a shock constructed in the manner hereinbefore described.

85 I claim as my invention:

90 1. A shocking truck, comprising a body, a platform hinged to the rear end of the body, and sheaf-bending devices comprising a standard rising from the body for supporting a sheaf, and rods projecting from 95 the platform and extending forwardly therefrom on opposite sides of the standard, the organization being such that when the platform is raised a sheaf may be placed on the standard and when the platform is 100 lowered the rods carried thereby engage the sheaf on opposite sides of the standard and bend it.

105 2. A shocking truck, comprising a body, a platform hinged intermediate its front and rear ends to the rear end of the body, a standard rising from the body in front of said platform and provided with an enlarged upper end to receive a sheaf, and rods secured to and extending forwardly from the 110 platform on opposite sides of said standard and which move with said platform and assume a position above the standard to permit a sheaf to be placed on said standard and which descend with said platform and 115 bend the sheaf, substantially as described.

120 In testimony whereof, I have hereunto subscribed my name.

GEORGE MARSHALL.
